UNITED STATES PATENT OFFICE.

GEORGE W. HARNES, OF ALLIANCE, NEBRASKA.

WASTE-CLEANING MACHINE.

1,105,512.

Specification of Letters Patent.

Patented July 28, 1914.

Application filed August 19, 1913. Serial No. 785,555.

To all whom it may concern:

Be it known that I, GEORGE W. HARNES, a citizen of the United States, residing at Alliance, in the county of Boxbutte and State 5 of Nebraska, have invented new and useful Improvements in Waste-Cleaning Machines, of which the following is a specification.

This invention is an improved machine for cleaning and recovering waste, especially 10 cotton waste which has been used in the journal boxes of car axles, the object of the invention being to provide an improved machine of this character which is adapted for separating the short, broken and worn 15 pieces of waste from the longer pieces and for also removing all foreign substances such as particles of Babbitt metal, dirt and the like from the longer waste so as to recover the longer waste from the worthless 20 particles and short pieces and enable the longer pieces to be reused, the invention consisting in the construction, combination and arrangement of devices hereinafter described and claimed.

25 In the accompanying drawings:—Figure 1 is a side elevation of a waste cleaning machine constructed in accordance with my invention. Fig. 2 is a vertical longitudinal sectional view of the same. Fig. 3 is a horizontal sectional view of the same on the plane indicated by the line *a—a* of Fig. 1. Fig. 4 is a vertical transverse sectional view 30 of the same.

The frame 1 of my improved waste cleaning machine is of oblong rectangular form 35 and is provided with supporting legs 2 which are arranged near the corners thereof. The supporting legs are provided with bearings 3 in which are mounted the shafts 4—5 of an endless carrier 6 which comprises a pair of rollers 7 on the shafts 4—5, spaced endless belts 8 which engage and connect the said rollers and transversely arranged spaced flight bars 9 which connect 40 the said belts and the ends of which are out-turned as at 10, so that the out-turned ends of the upper flight bars project upwardly, as shown in Figs. 1 and 2.

The shaft 4 is provided at one end with a 45 pulley 11. On the centers of the sides of the frame 1 are blocks or other suitable supports 12 which project upwardly therefrom and to which the ends of a bar 13 are secured, the bar being provided with a series of trans- 50 versely arranged spaced fingers 14 which

project from opposite sides thereof. This bar with its fingers constitutes a fixed comb.

A pair of shafts 15—16 are mounted for rotation in opposite directions, are arranged on opposite sides of and at a lower plane 60 than the fixed comb and are journaled in bearings 17 with which the frame 1 is provided. These shafts are, respectively, provided with spaced fingers 18—19 which project from opposite sides thereof and are arranged to pass through the spaces between the fingers of the fixed comb, the planes of revolution of the said fingers 18—19 being intersected by the fingers of the fixed comb. Each of these shafts with its fingers 65 constitutes a revoluble comb as will be understood. The shaft 15 has a spur gear 22 of the same diameter as the gear 20 so that the revoluble combs are caused to rotate in reverse directions as indicated by the arrows 70 in Fig. 2. The shaft 15 is also provided with a pulley 23 which is connected by a belt 24 to a double pulley 25 which is mounted on a stub shaft 26, said double pulley being connected by a twisted endless belt 27 75 to the pulley 11 of the roller shaft 4. Hence, the carrier 6 is also driven and is caused to move, as to its upper flights, in the direction indicated by the arrow in Fig. 3.

At the ends of the frame 1 are secured the 80 upper sides of a pair of inclined downwardly converging grates 28, the bars of which are preferably made of wires or rods of suitable gage having outturned lower ends 29 connected together by cross bars 30. 85

It will be noted upon reference to Figs. 1 and 2 of the drawings that the grates 28 discharge at their lower ends above and upon the endless carrier 6. A cover 32 is provided for the machine which is arranged at the 90 lower edges of its walls to fit around and to be fitted on and to be bolted or otherwise secured to the frame 1. This cover is provided at its center with a hopper 33.

In the operation of my improved machine, 100 the used waste as from the journal boxes of railway car axles is placed in the hopper 33 and drops on the fixed comb. The teeth of the revolving combs which pass downwardly and through the spaces between the teeth of 105 the fixed comb knock the waste from the fixed comb and separate the particles, the dirt, pieces of Babbitt metal and short, broken or worn particles of waste that drop through the spaces between the teeth of the 110

combs and also drop through the spaces between the flight bars of the endless carrier while the longer threads or pieces of waste are caught by the teeth of the revoluble 5 combs and thrown by them on the downwardly inclined grates 28 down which they slide and from which they drop on to the flight bars of the endless carrier, the said endless carrier delivering the recovered long 10 pieces of waste at one side of the machine. The grates 28 permit such pieces of short waste or foreign particles as may be in the long waste when the latter is thrown upon said grates to drop and become separated 15 from the long waste so that the long waste is separated and cleaned from the short waste and foreign particles both by the action of the fixed and revolving combs and by the action of the inclined grates.

20 The revolving combs rotate at a high rate of speed so that the teeth of the combs serve by striking the waste to knock the particles of waste apart and prevent them from being broken up and torn in pieces.

25 While I have herein shown and described a preferred form of the invention, I would have it understood that changes may be made in the form, proportion and construc-

tion of the several parts without departing from the spirit of the invention and within the scope of the appended claims.

I claim:—

1. In a machine of the class described, the combination of a fixed comb, and a pair of revolving combs on opposite sides of the fixed comb, a pair of downwardly converging inclined grates spaced apart and arranged under the revolving combs, and a carrier below and between the said grates and on which the latter discharges. 40

2. In a machine of the class described, the combination of a fixed comb, and a pair of revolving combs on opposite sides of the fixed comb, a pair of downwardly converging inclined grates spaced apart and arranged under the revolving combs, and a carrier below and between the said grates and on which the latter discharges, the said endless carrier being provided with spaced flight bars. 50

In testimony whereof I affix my signature in presence of two witnesses.

GEORGE W. HARNES.
